V. LAPLHAM, OF EL PASO, ILLINOIS.

Letters Patent No. 70,866, dated November 12, 1867.

IMPROVEMENT IN BOLT-FASTENING.

The Schedule referred to in these Letters Patent and making part of the same.

TO ALL WHOM IT MAY CONCERN:

Be it known that I, V. LAPLHAM, of El Paso, in the county of Woodford, and State of Illinois, have invented a new and useful Improvement in Bolt-Fastening; and I do hereby declare that the following is a full, clear, and exact description thereof, which will enable others skilled in the art to make and use the same, reference being had to the accompanying drawings, forming part of this specification.

Figure 1 represents my improved fastening attached to a thill-coupling bolt.

Figure 2 is a detail sectional view of the same, taken through the line x x , fig. 1, and showing in red a convenient tool for detaching the fastening.

Similar letters of reference indicate corresponding parts.

My invention has for its object to furnish an improved fastening for thill-coupling bolts, clevis-bolts, and other pivoting bolts, which will hold the bolt securely in place, and which can at the same time be easily and quickly attached and detached; and it consists in the fastening formed by the combination of the hinged parts, pivoted catch and rubber, or equivalent spring, with each other, as hereinafter more fully described.

A represents a thill-coupling, and B represents a thill-iron, about the construction of which parts there is nothing new. C is the bolt that passes through the eyes of the coupling and through the eye of the thill-iron. The bolt C has a neck formed upon its forward part for the reception of the fastening D, said neck having square shoulders to prevent the lateral movement of the said fastening upon the said bolt. The fastening D, when closed, has the general form of an ordinary nut, and its main part is made in two parts, d^1 and d^2 , hinged to each other at one end, as shown in fig. 2. d^3 is a catch pivoted in a recess formed in the free end of one of the parts, as d^2 , and having a projection or square hook formed upon the under side of its projecting end, which catches upon a shoulder formed at the bottom of a recess in the free end of the other part, as d^1 . d^4 is a rubber spring placed in a recess beneath the inner end of the catch d^3 , as shown in fig. 2, to hold the said catch securely in place when connecting the parts d^1 and d^2 . The catch d^3 , and the recesses in which it is placed, are so formed that the outer surface of the said catch may be flush with the surface of the ends of the parts d^1 and d^2 , so that no accidental blow upon the fastening can unfasten it. To detach the fastening the end of the catch must be pressed down with some sharp-pointed instrument, so as to compress the spring d^4 and raise the hooked end of said catch from the recess in the end of the part d^1 , which allows the fastening to be readily removed from the bolt.

I claim as new, and desire to secure by Letters Patent—

The bolt-fastening D, formed by the combination of the hinged parts d^1 and d^2 , pivoted catch d^3 , and rubber spring d^4 , or equivalent, with each other and with the bolt C, substantially as herein shown and described and for the purpose set forth.

V. LAPLHAM.
